ELECTRONIC COUNTING TUBE

Glenn E. Hagen, Redondo Beach, Calif., assignor to Northrop Aircraft, Inc., Hawthorne, Calif., a corporation of California

Application September 17, 1948, Serial No. 49,755

10 1 Claim. (Cl. 235—92)

15 My invention relates to electronic counters, and more particularly to an electronic counter tube and counting circuit.

Among the objects of the invention are:

20 To provide an electronic tube having a plurality of stable states;

To provide a circuit for such a tube whereby it can be used as an electronic counting device;

25 To provide a multi-stable state electronic tube and circuit suitable for counting and which will give a visual indication of the count;

To provide electronic counters in which the basic element is an electronic counting tube;

30 And to provide a simple efficient electronic tube suitable for digital counting.

In broad terms, the tube of the present invention has as many stable states as the number of digits of the number system being used. Means are provided to shift the tube from one stable state to the next in order, with a carry pulse being produced when the tube goes from the stable state corresponding to the largest digit to that corresponding to the smallest digit and vice-versa. Such tubes can be interconnected to increase the number of significant figures available.

35 My invention can be more readily understood by reference to the drawings, in which:

Figure 1 is a diagrammatic perspective view of a cathode-ray tube incorporating the present invention, the envelope being partially cut away.

Figure 2 is a plan view of the digit plate assembly of the tube shown in Figure 1.

Figure 3 is a wiring diagram of the tube of Figure 1.

Figure 4 is a diagram used as a symbol representing the tube of Figure 1.

Figure 5 is a wiring diagram showing the use of several tubes, as shown in Figure 1, to increase the number of significant figures that can be counted.

Figure 6 is a diagram of voltage changes in the circuit of Figure 5.

Figure 7 is a wiring diagram showing how a number can be transferred from one counter to another and to retain that number in the original counter.

Figure 8 is a wiring diagram of the pulse source used in the diagram of Figure 7.

Figure 9 is a wiring diagram of the gates used in the diagram of Figure 7.

Referring first to Figure 1, which shows diagrammatically in perspective the structure of a preferred counting tube built for and operable to count in the decimal system, in accordance with the present invention, a glass envelope 10 of the usual cathode-ray tube shape, is provided at the small end 11 with a hot cathode 12 and an apertured accelerating electrode 13. I am aware that many different and more complicated electrode arrangements are well known in the art for forming and accelerating an electron beam, and any such arrangement, termed here-in an electron gun, will be suitable for use in the tube to be described herein.

2

Thus, cathode 12 and accelerating electrode 13 represent an electron gun for generating a beam of electrons and for projecting this beam along the axis of the tube, if undeflected.

Shortly after the electron beam leaves the gun, a plurality of deflecting plates 6a to 9a, inclusive, are arranged around and spaced from the axis of the tube, each having a lead 6b to 9b, respectively, passing through envelope 10. Thus, ten deflecting plates and leads are provided.

Farther toward the large end of the tube, a control ring 14 is held concentrically around the axis of the tube by a ring lead 15, and adjacent the large end is positioned a digital plate assembly 16 positioned normal to the tube axis. Digital plate assembly 16 consists of ten coplanar side-by-side spirally wedge shaped digital plates 0 to 9, inclusive; the digital plates are insulated from each other and each is provided with an envelope lead 0c to 9c, respectively. The plates do not meet at the axis of the tube but stop short of the axis to form a central plate assembly aperture 17, and the curvature of the digital plate edges is such that all radii of the tube will intersect three plates. Each plate has a small beam aperture 18 between the inner and outer limit of the plates.

25 Thus, ten digital plates are provided, representing the digits 0 to 9, inclusive, together with their exterior leads.

Between plate assembly 16 and the large end of the tube, a cross bar 20 is extended normal to the axis of the tube, this bar having an exterior bar lead 21. From this bar, a control stud 22 is axially extended toward the cathode of the tube through plate assembly aperture 17 to a point slightly on the cathode side of control ring 14. The large end of the tube is provided with a fluorescent screen 24 of conventional type, on the inside thereof. As is customary, the tube is evacuated and sealed.

30 Various electrical connections to the tube just above described for establishing static states herein are shown in Figures 1, 2, and 3. The digital plates 0 to 9, inclusive, are supplied by a positive potential through a plate voltage line 25 carrying a positive potential, this line being connected to each digital plate through a plate load resistor 26. In practice, this load resistor can be a carbon ring of the proper thickness to give the desired resistances and attached to the digital plates 0-9, inclusive, on the screen side of the ring and to the plate voltage line 25 on the other side thereof. However, for simplicity of illustration, each digital plate is shown as connected to the plate voltage line 25 through a separate resistor.

45 Each plate 0 to 9, inclusive, is also connected to a corresponding deflecting plate in the group 6a to 9a, inclusive, through a deflecting plate resistor 27 but the particular deflecting plate to which a particular digital plate is connected is on the opposite side of the tube, as shown in Figure 1. The deflecting plate resistances 27 are of such high resistance that each deflecting plate will always be of a lower positive potential than that of the digital plate to which the deflecting plate is connected.

50 Each deflecting plate is also connected to the electron gun cathode through a cathode resistor 29. The complete resistance network of the tube is shown in Figure 3.

60 Two special output leads are also brought directly out from the tube, one lead 30 from the digital plate 0, corresponding to the smallest digit, and one lead 31 from the digital plate 9, corresponding to the largest digit, both leads by-passing the plate load resistors. When other radices are utilized, the smallest digit and largest digit connections will likewise be brought out. In this regard, while the decimal number system has been chosen herein for explanation purposes, the tubes and circuits will be similar for any number system, as long as the radix is small enough to allow the plate assembly of the counting tubes to be properly segmented.

Before proceeding to discuss the action of the counting tube, just above described in various counting circuits, it will be convenient to adopt a diagrammatic symbol for the tube, as shown in Figure 4, with the understanding that when this symbol is used in the circuit diagrams later described the tube the symbol represents is equipped with the resistance network as shown in Figure 3.

In Figure 4, the electron gun and the deflecting plates are represented as in the Rules of Practice of the Patent Office. The control ring 14 is represented by a barb. The control stud 22 is represented by an axial line alongside of the barb. Only two digital plates are shown, i. e., the 0 plate and the 9 plate as these leads are the only output leads. The lead 30 from the digital plate 0 leaves from the left of the symbol, and the lead 31 from the digital plate 9 is on the right of the symbol. The plate voltage line 25 is shown as connected to both digital plates 0 and 9 through the digital plate resistors 26. In case an additional control ring 14a is needed, this will be represented by a barb positioned below the barb for ring 14.

Considering the tube of Figure 1 to be energized to project a beam of electrons through the tube, this beam will pass between the deflecting plates 0a to 9a, inclusive, between the control ring 14 and the control stud 22, and will land at random on one of the digital plates 0-9 in the digital plate assembly. The resistances 26, 27, and 29 are so proportioned that the electron beam will have a stable position on whatever digital plate it falls on, with the beam falling on a digital plate at the position of the associated beam aperture 18. These stable states, with the beam in a particular position on one particular plate, are obtained because the beam electrons form a substantial part of the beam not passing through aperture 18 collect on the particular plate making it more negative and thus unbalances the combined field of the deflecting plates to deflect the beam to the proper position on the digital plate the beam is contacting. In the absence of additional deflecting forces the beam will stay on any digital plate it impacts, and will stay, under these same conditions, in the general area of aperture 18 on each plate.

As a portion of the beam normally passes through aperture 18, there will be a luminous spot produced on the fluorescent screen when the beam is on any digital plate, thereby providing a visual indication of where the beam is within the tube, so that a visual indication of the count within the tube can be seen at all times.

An alternate method of obtaining a visual indication of beam position is to coat the cathode side of the digital plates with fluorescent material and observe the luminous spot position by a conical mirror positioned on the cathode side of the digital plates and viewed through the central digital plate assembly aperture 17.

When a beam aperture 18 is used in each digital plate, the size and intensity of the spot on the digital plate is adjusted so that the part of the beam absorbed by the plate is sufficient to lower the potential of the connected deflecting plate, and the part passing to the fluorescent screen is sufficient to cause a luminous spot thereon.

When the counter tube as described is first energized, the beam will rest on one of the digital plates, but on no particular one. For this reason, unless the beam happens to be on digital plate 0, a single short negative pulse is initially applied to the digital plate 0 lead 30 of the tube which causes a drop in potential on the deflecting plate 0a opposite the digital plate 0. This causes the electron beam to be deflected so that it terminates on the digital plate 0 directly over its beam aperture 18. This will be called point P₁, as shown in Figure 2. When the tube is in this stable condition, a positive input pulse, applied to the control ring 14 of the tube, will cause the electron beam to move outwardly

and travel from point P₁ to point P₂ as shown in Figure 2, point P₂ being on digital plate 1. As long as the positive pulse on the ring lasts, the beam will stay at point P₂ because of deflection by ring 14 and because the voltage change on deflecting plate 1a caused by the absorption of the beam on plate 1 causes the deflecting plate 1a opposite digital plate 1 to be of lower positive potential than the other deflecting plates, thereby holding the beam on digital plate 1. When this positive ring pulse ends, however, the beam will move inwardly to its stable position on digital plate 1, i. e., to point P₃ which is at the beam aperture 18 in digital plate 1. The next positive pulse applied to control ring 14 will move the beam to digital plate 2, and so on around the digital plate assembly in additive direction, in accordance with the number of positive pulses applied to the control ring 14.

If, however, the first pulse applied to control ring 14 after positioning the beam on digital plate 0 is negative, then the terminus of the electron beam on the digital plate assembly will change from point P₁ on digital plate 0 to point P₄ on digital plate 9. When the negative ring pulse ceases, the beam will remain on digital plate 9 but will return to point P₅ on this latter plate, point P₅ being the beam aperture 18 position, and the stable position of the beam on digital plate 9.

Thus, positive pulses to control ring 14 will cause additive counting, whereas negative pulses on this same ring will cause subtractive counting.

Exactly the same effect will be caused by applying negative pulses to control stud 22 for additive counting, and applying positive pulses to stud 22 for subtractive counting. However, for circuit separation, it is convenient to use both control electrodes for beam control. So that the beam can be spotted on any plate desired, each plate is provided with a setting lead 3S.

To increase the number of significant figures available in a counter, more than one tube, such as that just described, is used. Figure 5 is a diagram showing one type of counting circuit utilizing the above described counting tube, the symbols for which are as described for Figure 4. In this diagram, the digital plate 9 lead 31 and the digital plate 0 lead 30 of one tube are connected to the control ring 14 and control stud 22 of the next tube with a condenser 40 placed in each connection. Two resistors 41 and 42 are placed in series across these connections on the ring and stud side of condensers 40 with a grounded tap 43 between the resistors 41 and 42, each resistor being provided with a voltage adjustment 43a.

Assume that the numbers in the first four tubes A, B, C, and D, as shown in Figure 5, are set to be 9, 0, 9, and 2, respectively. This setting is done by applying a negative pulse to the particular plates in the particular tubes through the appropriate setting lead 3S or leads 30 or 31.

Thus, the number 2909 is set up in the counter. Also assume that additive counting is taking place, i. e., that positive pulses are fed into the control ring input lead 15 to tube A. As indicated in Figure 6, the voltage at the digital plate 9 lead 31 in tube A of Figure 5 will be on the lower portion of the solid line (marked X) since the number 9 is in tube A; also the voltage at digital plate 0 in tube A of Figure 5 is indicated by the upper dotted line (marked Y) in Figure 6. The next positive input pulse at the ring input lead 15 to tube A causes the terminus of the electron beam to switch from the nine segment to the zero segment of tube A and thereby cause the voltage at point X to increase, and the voltage at point Y of Figure 5 to decrease as indicated by the crossing solid and dotted lines in Figure 6. This voltage difference across resistors 41 and 42 following tube A of Figure 5, when placed across the control ring lead 15 and control stud lead 21 in tube B, is sufficient to cause the number in tube B to increase from zero to one. Thus, one input pulse has resulted in the number in the counter

70 to increase from 2909 to 2910. This shift in tube B does

not cause any action in tube C because no beam shift occurred between digital plates 0 and 9 in tube B.

Again, assume that the numbers 0, 0, 0, and 1 are in tubes A, B, C, and D, respectively, of the counter in Figure 5 (representing the number 1000) and that subtractive counting is taking place. When either a negative pulse appears at the ring input lead 15 of tube A or a positive pulse appears at stud input lead 21 of tube A, the electron beam will shift from the digital plate 0 to the digital plate 9 in tube A. In doing so, the voltages at the digital plates 0 and 9 of tube A will be similar but opposite to the voltages indicated by X and Y in Figure 6. As a result, a voltage will appear across resistors 41 and 42 following tube A in Figure 5 of such magnitude and such polarity that it causes tube B to be switched from zero to nine. Tube B repeats the action and switches tube C from zero to nine, and this causes tube D to be switched from one to zero. Thus, the number in the counter has been changed from an original value of 1000 to a value of 0999 by an input of one subtractive pulse. The system of Figure 5 will, therefore, count pulses additively or subtractively applied to the input of tube A.

The circuit shown in Figure 7 can be used to transfer a number from one counter to another, and still retain that number in the original counter.

Four counter tubes L, M, N, and O are set up to count as shown in Figure 5. These counter tubes are the same as has hereinbefore been described, with the single exception that an auxiliary control ring 14a is inserted in each tube just below ring 14. Ring 14a acts exactly the same as ring 14 to move the electron beam, and is used separately because circuit separation is needed.

The digital plate 9 of each tube L, M, N, and O is provided with a gate lead 45, the gate leads from tubes L, M, N, and O connecting with gates G₁, G₂, G₃ and G₄, respectively. Each gate is also provided with a pulse source lead 46 connected to a pulse source line 47. Line 47 is energized by a pulse source PS, this pulse source being under the control of a transfer pulse input 48. Circuits for both gate and pulse sources will be described later. Pulse source line 47 also energizes the auxiliary rings 14a through auxiliary ring leads 49.

Each gate G₁, G₂, G₃ and G₄ is provided with an output line 45a. These lines 45a run from the respective gates to the stud leads 21 of a second bank of counter tubes P, Q, R, and S, respectively.

Tubes P, Q, R, and S are the same as those used in the circuit of Figure 5, no auxiliary ring being needed. Tubes P, Q, R, and S are also connected as shown in the circuit of Figure 5, with the single exception of the provision of a time delay device D between each set of resistors 41 and 42 and the ring lead 15 and stud lead 21 of the following counter tube. This delay device may be of the acoustical type such as, for example, the crystal-mercury delay device well known in the art. It will be noted that when hooked up as above described, the stud of each tube P, Q, R, and S is connected both to the respective gate and to the output of the preceding tube.

The first tube L of the bank L, M, N, and O is provided with counting input leads 15 and 21 going to the ring 14 and stud 22 of tube L, respectively, and the first tube P of the tube bank P, Q, R, and S is also provided with counting input leads 15 and 21, respectively, connected to the ring 14 and stud 22 of tube P.

From the above description of the circuit of Figure 7, it will be seen that when gates G₁, G₂, G₃ and G₄ are open and the pulse source PS is not operating, any four digit number desired can be set up in tube bank L, M, N, and O and any four digit number desired can also be set up in tube bank P, Q, R, and S through their respective counting input without interaction between the banks, as this interaction can take place only when the pulse source circuit is initiated by a transfer pulse.

The pulse source PS used in the circuit of Figure 7

is shown in Figure 8. MV represents an oscillator pulse forming circuit such as, for example, a multivibrator. This multivibrator runs continuously and its output is applied to the cathode 50 of a crystal diode 51 through cathode wire 52. Resistances 53 and 54 have one end connected together and to cathode wire 52. Resistance 53 is connected at the other end to a source of positive potential, and the other end of resistance 54 is grounded. These two resistances 53 and 54 maintain the direct current voltage level of the cathode 50 of the diode constant. The plate 55 of the diode is connected to the output line 47 of the pulse source PS, and plate resistances 57 and 58 are connected together at one end and to output line 47. The other end of plate resistor 57 is connected to the digital plate 0 of a pulse source counter tube 60 similar to that shown in Figure 1, and the other end of plate resistor 58 is grounded. Plate resistors 57 and 58 serve to maintain the direct current voltage level of the plate 55 of the diode at one of two values. These values are determined by the condition of the digital plate 0 of the pulse source counter tube 60. Ring 61 of the pulse source counter tube 60 is connected to transfer pulse input wire 48, this latter wire also being connected to output line wire 47 of the pulse source.

When the beam of the pulse source counting tube 60 is on its digital plate 0, the positive voltage at the top of plate resistance 57 is sufficiently low that the voltage at the plate 55 of the diode is always below that of the cathode 50; thus, no pulses pass from the multivibrator through the diode to the pulse output line wire 47. A single transfer pulse applied to input wire 48 will switch the counting tube from zero to one and also this pulse will feed directly to the output line 47 of the pulse source. By switching the counting tube from zero to one, the voltage of the plate of the crystal diode is caused to rise, thereby allowing pulses from the multivibrator to pass through the diode to the output line 47. However, each pulse that passes through the crystal diode is also fed back into the ring 61 of the pulse source counting tube 60 and causes the pulses to be counted therein as they pass to the output of the pulse source. After nine pulses from the multivibrator have passed to the output line 47, the pulse source counting tube 60 will be back to zero and immediately the crystal diode will block further output from the multivibrator. Thus, ten pulses have appeared at the pulse source output line 47; one from the initial transfer impulse applied to input wire 48 and nine from the multivibrator MV. These ten pulses appear all along pulse output line 47 at the gate inputs 46.

One of the gates G₁, G₂, G₃ or G₄ used in the counting circuit illustrated in Figure 7 is shown in Figure 9. The digital plate 9 of one of the counter tubes L, M, N, or O, is connected by gate lead 45 to the grid 70 of a vacuum tube 71 through a direct current blocking condenser 72. Grid 70 is connected to the tube cathode 73 through grid return resistor 74 and biasing resistor 75, the latter being shunted by capacitor 76. Anode 77 is provided with the usual positive potential.

A load resistor 78 is connected to grid return resistor 74 and bias resistor 75 and the other end of the load resistor 78 is grounded. Potentials developed across load resistor 78 are applied to a detector grid 80 of a second tube 81 through input condenser 83 and to the cathode 82 of said latter tube, detector grid 80 being provided with a return resistor 84 having a high resistance. Pulse source lead 46 is connected to an input grid 86 in second tube 81, the latter being provided with an output resistor 87 and a D. C. blocked connection 88 to gate output line 45a. As will be seen from Figure 9, the input grid 86 of the gate is connected to the output of the pulse source PS via line 47 and the output 45a of the gate goes to a stud in one of the tubes P, Q, R, or S.

Tube 71 is operated near cut-off for the tube. Thus, negative pulses arriving at the grid 70 of this tube from the digital plate 9 of the counting tube to which this grid

is connected merely drive the tube 71 below cut-off and are of no consequence.

When the counting tube to which the first tube 71 of the gate is connected goes from the number eight to nine, for example, the gate is unaffected and second tube 81 is able to conduct. However, when the number in this counting tube increases from nine to zero, a positive pulse is applied to the grid 70 of tube 71 and tube 71 momentarily conducts; the blocking condenser 72 preventing a long lasting direct current positive voltage from being impressed on the grid of tube 71. When tube 71 conducts, it energizes tube 81 through input condenser 83, and places a positive pulse on the detector grid 80 of second tube 81. As this grid 80 of tube 81 is driven positive, it starts to draw current. When the positive pulse on the grid 80 of second tube 81 is terminated, this grid 80 will be at a more negative voltage than it was under initial conditions, due to the grid current. This negative voltage is slowly eliminated by a leakage current through return resistor 84, but the high resistance of return resistor 84 prevents immediate return to original conditions. While this negative voltage is present on the grid 80 of tube 81, the tube 81 is not capable of conducting and will not pass pulses from its input to output. Thus, tube 81 operates as a gate, open, i. e., capable of conducting until the number in the counting tube L, M, N, or O switches from nine to zero and which then closes, i. e., is not capable of conducting, and remains closed until after the counting tube of the connected counter tube of Figure 7 has been cycled with ten pulses from the pulse source PS.

The action of the circuit shown in Figure 7, including the circuits shown in Figures 8 and 9, as used to transfer a number from tube counters L, M, N, and O to tube counters P, Q, R, and S, and to retain that number in tube counters L, M, N, and O, is as follows:

Assume that counter tubes L, M, N, and O have the numbers 5, 9, 0, and 1 (1095) respectively placed in them, and that tubes P, Q, R, and S all have the number zero in them. Note that there is an unbroken lead from a pulse source, PS, to the auxiliary rings 14a of tubes L, M, N, and O of the first counter. Also a lead is available from the pulse source PS to gates G₁, G₂, G₃, and G₄, whose inputs are connected to the digital plate 9 leads of tubes L, M, N, and O, respectively. The outputs of the gates G₁, G₂, G₃ and G₄ pass to the studs of tubes P, Q, R, and S. The output of the pulse source PS is bursts of ten positive pulses. The delay devices D, located between each counting tubes P, Q, R, and S, will permit carry pulses between these tubes to pass only after the pulse source has completed its cycling of the first counter.

The gates G₁, G₂, G₃, and G₄ are open, i. e., capable of conducting to their respective tubes P, Q, R, or S. A transfer pulse is applied to transfer pulse input 48 to start the pulse source operating. This first output pulse from the pulse source, through the auxiliary ring 14a connections, increases the number in tube L from 5 to 6, increases the number in tube M from 9 to 0 and thereby closes gate G₂, increases the number in tube N from 0 to 1, and increases the number in tube O from 1 to 2. Since all of the gates were initially open to pass pulses from the pulse source to tubes P, Q, R, and S, one subtractive pulse (a positive pulse to the stud) has also been fed to tubes P, Q, R, and S through the gates. Consequently, the second counter now reads 9999. However, when tube M goes from 9 to 0 it closes gate G₂ and thereby prevents further subtractive pulses from entering tube Q. Gate G₂ will remain closed until after the first counter has been completely cycled with ten pulses.

Normally, when tube M increased its number content from 9 to 0, a carry pulse would be passed to the next tube N through the condenser 40, 40a and resistor 41, 42 network. However, the time constant of this network between each of the tubes L, M, N, and O can be suitably designed such that the carry pulse from a preceding tube such as M, that was initiated in tube M by a pulse

from the pulse source PS, arrives in the following tube, such as N, at substantially the same time as the pulse from the pulse source arrives in tube N.

The carry pulse and the pulse from the pulse source are thus virtually superimposed and tube N will not recognize the carry pulse as such, separate from the pulse from the pulse source. The fifth pulse from the pulse source will switch tube L from 9 to 0 and close gate G₁. The ninth pulse from the pulse source will switch tube O from 9 to 0 and close gate G₄. The tenth input pulse will switch tube N from 9 to 0 and close gate G₃.

As a result of cycling each tube L, M, N, and O of the first counter with ten pulses, and by designing the carry pulse forming circuit so that carry pulses as such are not recognized in any of the tubes of the first counter when the pulse source is operating, the number 1095 will be in both counters. Tube P has counted backward from zero to five; tube Q has counted backward from zero to nine; tube R has counted backward from zero to zero; and tube S has counted backward from zero to one. If the number 1095 is transferred again from the first counter to the second, the carry pulses from tube P to tube Q and from tube R to tube S will be delayed and will take place after the cycling of the first counter, which gives 2190 in the second counter.

Since the second counter has each tube counting backward, the carry pulses will be of a subtractive nature. Therefore, the carry pulse leads 30 and 31 are reversed in the second counter, i. e., instead of connecting the digital plate 9 of one tube to the ring of the next and the digital plate 0 of the first tube to the stud of the second, the digital plate 0 of the first tube is connected to the ring of the second and the digital plate 9 of the first tube is connected to the stud of the second. This type of connection has been made in Figure 7.

If the inputs from the first counter to the second counter were to be reversed and applied to the rings of each counting tube P, Q, R, and S instead of to the studs as shown in Figure 7, the number in the first counter would be transferred negatively to the second. In this latter case, the carry pulse leads in the second counter would have to be reversed again.

The counting tube described above and the associated counting circuits shown herein offer the advantages of high-speed electronic counting without the disadvantage of using a multiplicity of tubes to secure a few significant figures. Since an ordinary electron tube has only two stable states, i. e., non-conducting or conducting, a great many tubes are necessary to have a counter with any sizable number capacity. A single electron tube with many stable states as described herein alleviates several difficulties inherent with the use of many electron tubes, i. e., probability of tube failure, large power requirements, a change in the radix of the number system used, etc.

What is claimed is:

In combination with a plurality of electronic counting tubes each having as many stable states as there are digits in the number system being counted, each having input means when energized to serially shift said tube from one stable state to the next in either direction and each having output means for producing a pulse when passing between the stable state representing the smallest digit and the stable state representing the largest digit, a first bank of tubes representing a plurality of significant figures, the output of each of said tubes being connected to the next by means for discriminating the direction of the pulse in said output means to the input means of the next tube to cause said tube to shift its stable state in the proper direction, means for applying additive or subtractive pulses to the first tube in said first bank to cause counting in all significant figure tubes, a second bank of similar tubes representing the same plurality of significant figures and connected to count as recited for said first bank, each tube of said first bank being connected to

cause the tube in the second bank of tubes representing the same significant figure to count, a gate in each of said latter connections, a pulse source having an output, means for limiting one cycle of pulses from said source to a number corresponding to the number of stable states in each tube, the output of said pulse source being simultaneously connected to the input of each tube of said first bank of tubes, means operated by shift of the stable state in each tube of the first bank to the stable state representing the largest digit to render said gates non-conducting, the discriminating means between each tube of said second bank being provided with a delay device to provide time for one complete cycling of each tube of said first bank with pulses from said pulse source before energizing the following tube in said second bank whereby a number counted in said first bank is transferred to said second bank with retention of the number transferred in said first bank.
